UNITED STATES PATENT OFFICE

136,797

DESIGN FOR A LIGHTING FIXTURE

Waldo T. Mareck, Minneapolis, Minn.

Application August 13, 1943, Serial No. 110,909

Term of patent 3½ years

To all whom it may concern:

Be it known that I, Waldo T. Mareck, a citizen of the United States, residing at Minneapolis, in the county of Hennepin and State of Minnesota, have invented a new, original, and ornamental Design for a Lighting Fixture, of which the following is a specification, reference being had to the accompanying drawing, forming part thereof.

Referring to the drawing:

The single figure of the drawing is a bottom perspective view showing a light fixture of my new design and in which the side and end not shown are substantially the same as the side and end shown.

I claim:

The ornamental design for a lighting fixture, as shown and described.

WALDO T. MARECK.
